(1026 75th St., Brooklyn, N.Y.)

Filed Apr. 28, 1961, Ser. No. 64,932

Term of patent 7 years

(Cl. D29—23)

Fig. 2.

FIG. 1 is a front elevational view of a wall plaque, showing my new design, and

FIG. 2 is a top plan view of the same. The rear face of the wall plaque is plain.

The dominant features of my design reside in the portions shown in full lines.

I claim:

The ornamental design for a wall plaque, substantially as shown and described.
